CLAIM

The ornamental design for a pile guide with attachment wings as shown and described.

DESCRIPTION

FIG. 1 is a top perspective view of a pile guide with attachment wings showing the new design;
 FIG. 2 is a front elevation of the pile guide with attachment wings;
 FIG. 3 is a rear elevation of the pile guide with attachment wings;
 FIG. 4 is a top plan view of the pile guide with attachment wings; and
 FIG. 5 is a bottom plan view of the pile guide with attachment wings.
 FIG. 6 is a right side elevation of the pile guide with attachment wings; and,
 FIG. 7 is a left side elevation of the pile guide with attachment wings.

1 Claim, 7 Drawing Sheets
